Primary Examiner — Thomas Johannes*Assistant Examiner* — Chelsea Sealey(74) Attorney, Agent, or Firm — Stein IP, LLC(57) CLAIM

The ornamental design for a wireless power receiving apparatus of the portable electronic device, as shown and described.

DESCRIPTION

FIG. 1 is a perspective view of the wireless power receiving apparatus of the portable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the article in broken line indicate unclaimed subject matter that forms no part of the claimed design.

1 Claim, 7 Drawing Sheets(56)
